[57] **CLAIM**

The ornamental design for a bottle, substantially as shown and described.

DESCRIPTION

FIG. 1 is an elevational view of a bottle showing my new design, the opposite side being the same in appearance;

FIG. 2 is a top plan view;

FIG. 3 is an elevational view looking from the right of FIG. 1, the opposite side being the same in appearance; and

FIG. 4 is a fragmentary sectional view on the line 4—4 of FIG. 3.

FIG. 1

FIG. 2

FIG. 3

FIG. 4
